ABSTRACT OF THE DISCLOSURE

A drill boom is longitudinally extensible and contractible by a power cylinder. The drill boom extension mechanism includes a boom extension member longitudinally slidably guided on the one hand in a journal bearing affixed to the outer end of the drill boom and on the other in a guiding sleeve made in one piece with the journal bearing and extending into the drill boom. The guiding sleeve has such spacing therearound within the boom as to avoid deformation thereof against interior parts of the drill boom during normal deflection of the latter. The guiding sleeve has furthermore longitudinal grooves cooperating with wedges on the boom extension member for guiding the latter non-rotatably in the drill boom.

This invention relates to drill booms and more particularly to longitudinally adjustable drill booms adapted for positioning a drilling apparatus to different alternative drilling positions with respect to a work surface. Drill booms are normally subjected to fluxural stress under the influence of their own weight and of feeding forces causing considerable deflection of the end of the boom vertically or in a transverse plane defined by the drilling direction. During deflection of conventional booms of the longitudinally extensible type there is usually the risk of elongated parts of the boom extension mechanism becoming stuck in the journal bearing and guides thereof so that the latter may be deformed permanently to such an extent that the longitudinal adjusting function is imperiled. A constructional reinforcement of the elements and guides of the boom extension mechanism does not result in a satisfactory solution here because of the undesirable increase in weight. It is therefore an object of the invention to provide an improved boom extension mechanism for a longitudinally adjustable drill boom which mechanism during deflecting load on the drill boom is relieved from deformations to such an extent that sticking is entirely avoided. Another object of the invention is to create simultaneously herewith a constructional solution presenting a low total weight for the elements included in the boom extension mechanism.

For these and other purposes there is according to the invention provided a longitudinally adjustable drill boom adapted for positioning a rock drilling apparatus to different alternative drilling positions with respect to a work surface and comprising a boom support, a hollow drill boom swingably mounted at the inner end thereof on said boom support, a journal bearing at the outer end of said drill boom, an adjusting head having a boom extension member thereon received in said journal bearing for slidably supporting said adjusting head thereon, a drilling apparatus adjustably supported on said adjusting head, a power cylinder connected to said drill boom and to said adjusting head for adjusting the length of said drill boom between said adjusting head and said boom support, a guiding sleeve affixed to the outer end of the drill boom

2

and extending into the interior of the drill boom around said boom extension member, means for guiding the inner end portion of said boom extension member longitudinally slidably in said guiding sleeve, and said guiding sleeve having such clearance peripherally therearound in said drill boom as to avoid deformation of said guiding sleeve against interior parts of said drill boom during normal deflection of the latter. As a result of the chosen solution the entire sleeve will follow the angular movements of the end of the boom during deflection and will stay straight so that sticking of the boom extension member is avoided.

The above and other objects of the invention will become obvious from the following description and from the accompanying drawings in which a preferred embodiment of the invention is illustrated by way of example. It should be understood that this embodiment is only illustrative of the invention and that various modifications thereof may be made within the scope of the claims.

15 In the drawings FIG. 1 shows a diagrammatic side view of a drill boom together with a drilling apparatus carried thereby, an extended position of the drill boom being indicated by broken lines. FIG. 2 shows an enlarged fragmentary vertical section through the inner end of drill boom in FIG. 1. FIG. 3 is a cross section through the drill boom on the line 3—3 in FIG. 2. FIG. 4 shows on the same scale as FIG. 2 a fragmentary vertical section through the outer end of the drill boom. FIG. 5 is a cross section on the line 5—5 in FIG. 4. FIG. 6 is a cross section on the line 6—6 in FIG. 4. FIG. 7 finally shows a partly sectional side view of a guiding sleeve also shown in FIGS. 2 and 4 and intended for receiving therein the boom extension member of the drill boom.

20 In FIG. 1 the drill boom 10 is supported at the inner end thereof vertically and laterally pivotally about suitable axles on a conventional boom support 12 which is affixed to an element 13 forming part of a drill wagon or rig, not shown. The elevation and side swing angles of the drill boom are set by means of conventional hydraulic cylinders journaled on the boom support 12. The drill boom 10 carries at the outer end thereof an adjusting head 14 for mechanized orientation of a drilling apparatus including a feed shell 16 provided with a rock drill 15 and a power feed thereon for the rock drill 15. Furthermore there are supported conventional hydraulic cylinders, not shown in detail, on the adjusting head 14 for purposes of positioning said drilling apparatus.

25 The adjusting head 14 includes a fork 11 as a carrying member which is fixed by screws to a cylindrical hollow boom extension member 17. The boom extension member 17 is slidably guided in a journal bearing 18 at the outer end of the drill boom 10. The latter is made with a hollow straight jib portion 10¹ which is quadrangular in cross section and into the interior of which the boom extension member 17 projects. The jib portion 10¹ is pivotally journaled on the boom support 12 by an angular arm 10¹¹ extending upwardly and angularly outwardly from the upper side side of the jib portion 10¹. Between the folk 11 and an outer flange on the boom extension member 17 is bolted an intermediate piece 19 extending into the boom extension member 17 from the forward end thereof. The intermediate piece 19 carries journaling lugs 20 at the inner end thereof. A pivot 21 is carried by the journaling lugs 20 which pivot 21 at the middle portion thereof is provided with a ring 22 having a spherical bearing surface, FIG. 5.

30 The jib portion 10¹ of the drill boom 10 carries flanges 23 at the outer end thereof and flanges 24 at the inner end thereof. The journal bearing 18 is supported by an outer portion of a tubular guiding sleeve 25 which by means of a flange 32 is affixed to the flanges 23 together

with a cover ring 26 slidably surrounding the boom extension member 17 and a centering ring 27. The guiding sleeve 25 extends far into the interior of the jib portion 10¹ and has a considerable radial spacing or clearance 43 peripherally therearound with respect to the inner walls of the jib portion 10¹. The guiding sleeve 25 is provided with a pair of diametrically arranged guideways or guiding grooves 28 which extend along the major portion of the length thereof. In the guiding grooves 28 is non-rotatably slidably a pair of guides or wedges 29 which are inserted in recesses 30 at the inner end of the boom extension member 17 and bolted to the latter. In connection with the grooves 28 in the guiding sleeve 25 there are arranged openings 31, FIG. 7, for inserting the wedges 29 during assembly. The wedges 29 are surrounding by slide plates 45 of bronze filling the radial play between the guiding sleeve 25 and the boom extension member 17 and providing a journal for the inner end of the latter whereby said inner end is supported longitudinally slidably in the drill boom.

The inner end of the journal bearing 18 is supported by a peripheral support member 32 which is fixed to the inside of the jib portion 10¹ at some distance from the flange 32, FIG. 4. To the inner flanges 24 of the jib portion 10¹ is affixed a bracket or a cover 33 which carries inner journaling lugs 34. Between the journaling lugs 34 is seated a pivot 35 on which a piston rod 36 is journalled. The piston 36 is included in a preferably hydraulically actuated power cylinder 37. The operating conduits 39, 40 of the power cylinder 37 are led through the cover 33 to the piston rod 36. The piston rod 36 is made hollow and carries centrally therein an inner tube 38. The conduits 39, 40 communicate respectively via the piston rod 36 and via the inner tube 38 with the opposite ends of a piston 44 slidably and sealingly guided in the cylinder 37. By alternate supply and draining of pressure fluid to and from the conduits 39, 40, the working chambers of the cylinder 37 can alternately be pressurized so that the cylinder 37 is displaced within the jib portion 10¹ in a direction away from or towards the pivot 35. The outer end of the cylinder 37 carries a lug 41 thereon in which is inserted a spherically recessed bearing ring 42, FIG. 5, cooperating with the spherical ring 22 on the pivot 21.

Displacement of the cylinder 37 outwardly or inwardly in the jib portion 10¹ is transmitted via the pivot 21 to the intermediate piece 19 and the adjusting head 14 so that the boom extension member 17 is caused to slide outwardly or inwardly in the journal bearing 18 for example from the position shown by full lines in FIG. 1 to the position 14¹-16¹ depicted by broken lines therein or to some position therebetween. Rotation of the boom extension member 17 is prevented by the guides or wedges 29 sliding in the grooves 28 whereby the latter provide guideways for the wedges 29. During such longitudinal adjustment the boom extension member 17 is always rigidly supported in the journal bearing 18 and by the sliding plates 45. Because of the weight of the drilling apparatus 15, 16 and the adjusting head 14 and also during action of feed reaction forces against the feed shell 16 the drill boom 10 is deflected. Since the guiding sleeve 25 takes part in the angular movement caused by the deflection at the outer end of the drill boom 10 and since the clearance 43 will be chosen so large that the inner portion of the guiding sleeve 25 during normal deflection will not be deformed by contacting the inner walls of the jib portion 10¹, FIG. 2, permanent deformation and sticking of the elements within the drill boom 10 is avoided. Simultaneously there is received a lightweight and simple boom design which makes possible the use of a power cylinder 37 of standard make and is suitable for providing the basic unit of a boom component system which may be combined in a rational way for providing various functions.

During drilling the spherical ring connection 22, 42 on the pivot 21, FIG. 5, as well as the pivot 21 make possible limited pivotal movement in two planes perpendicular to one another. This permits limited universal angular movability in any direction between the intermediate piece 19 and adjusting head 14 on the one hand and the power cylinder 37 on the other. Thanks to this the cylinder 37 can freely adapt itself to deflections of the outer end of the drill boom 10.

10 What I claim is:

1. A longitudinally adjustable drill boom adapted for positioning a rock drilling apparatus to different alternative drilling positions with respect to a work surface and comprising a boom support, a hollow drill boom 15 swingably mounted at the inner end thereof on said boom support, a journal bearing at the outer end of said drill boom, an adjusting head having a boom extension member thereon received in said journal bearing for slidably supporting said adjusting head thereon, a drilling apparatus 20 adjustably supported on said adjusting head, a power cylinder connected to said drill boom and to said adjusting head for adjusting the length of said drill boom between said adjusting head and said boom support, a guiding sleeve affixed to the outer end of the drill boom 25 and extending into the interior of the drill boom around said boom extension member, means for guiding the inner end portion of said boom extension member longitudinally slidably in said guiding sleeve, and said guiding sleeve having such clearance peripherally therearound in said drill boom as to avoid deformation of said guiding sleeve against interior parts of said drill boom during 30 normal deflection of the latter.

2. A drill boom according to claim 1 in which there are provided longitudinal guideways on said guide sleeve, 35 and cooperating guides at the inner end of said boom extension member in axially slidably engagement with said guideways for guiding said boom extension member non-rotatably during longitudinal sliding movement thereof in said guiding sleeve.

3. A drill boom according to claim 1 in which said drill boom has flange means at the outer end thereof and said journal bearing is made as an elongated tubular member in one piece with said guiding sleeve and is affixed to said flange means.

4. A drill boom according to claim 1 in which said boom extension member is hollow and said power cylinder is mounted in said boom extension member with one end thereof connected to said adjusting head and the other to said drill boom.

5. A drill boom according to claim 4 in which the connection between said one end of said power cylinder and said adjusting head includes pivot means in two planes perpendicular to one another for permitting universal angular adaptability between said power cylinder and said head.

6. A drill boom according to claim 1 in which said drill boom is provided with inner and outer flanges respectively at the inner and outer end thereof, a through cavity in said drill boom between said flanges, said journal bearing and guiding sleeve being made in one piece as an elongated tubular member affixed to said outer flanges and extending into said cavity, a bracket connected to the inner flanges of said drill boom, and said power cylinder being mounted within said boom extension member with one end thereof connected to said boom extension member and adjusting head and the other to said bracket.

7. In an extensible and contractible drill boom an elongated hollow jib portion having flanges at the opposed ends thereof and a through cavity straightly therebetween, a tubular elongated guiding sleeve extending into said jib portion and being connected to the flanges at one end of said jib portion, a bracket connected to the flanges at the other end of said jib portion, a journal bearing 70 in said guiding sleeve at the end thereof connected to

said jib portion, an elongated hollow boom extension member longitudinally slidably guided in said guide sleeve as well as in said journal bearing, a power cylinder in said boom extension member connected therebetween said bracket for longitudinal adjustment of said boom extension member relative to said jib portion, and said guiding sleeve having such clearance peripherally theraround in said jib portion as to avoid deformation of said guiding sleeve against interior parts of said jib portion during normal deflection of the latter.

8. In a drill boom according to claim 7 longitudinal grooves on said guide sleeve, and wedges affixed to said boom extension member and in axially slidably engagement with said grooves for guiding said boom extension member non-rotatably during longitudinal sliding movement thereof in said guiding sleeve.

9. In a drill boom according to claim 7 the connection between said power cylinder and said boom ex-

tension member including pivot means in two planes perpendicular to one another for permitting universal angular adaptability between said power cylinder and said boom extension member.
